[57] CLAIM

The ornamental design for a leaner discharge unit, as
shown and described.

DESCRIPTION

FIG. 1 is a perspective view of the leaner discharge unit
showing my new design;

FIG. 2 is a front view thereof;

FIG. 3 is a right side view thereof, the left side view
being a mirror image thereof;

FIG. 4 is a top view thereof;

FIG. 5 is a rear view thereof; and,

FIG. 6 is a bottom view thereof.
